(57) **CLAIM**

The ornamental design for a dynamic spinal plate implant, as shown and described.

DESCRIPTION

FIG. 1 is a front perspective view of a dynamic spinal plate implant showing my new design;

FIG. 2 is left side perspective view thereof;

FIG. 3 is a right side perspective view thereof;

FIG. 4 is a top plan view thereof;

FIG. 5 is a front elevational view thereof;

FIG. 6 is a bottom plan view thereof;

FIG. 7 is a rear elevational view thereof;

FIG. 8 is a cross-sectional view thereof taken along line 8—8 in FIG. 5 shown in fragment and on an enlarged scale; and,

FIG. 9 is a cross-sectional view thereof taken along line 9—9 in FIG. 6 shown in fragment and on an enlarged scale.
